UNITED STATES PATENT OFFICE

135,473

DESIGN FOR A METAL CUTTING MACHINE OR SIMILAR ARTICLE

Ewald Schutz, Lancaster, Pa., assignor to De
Walt Products Corporation, Lancaster, Pa., a
corporation of Pennsylvania

Application February 6, 1942, Serial No. 105,663

Term of patent 14 years

To all whom it may concern:

Be it known that I, Ewald Schutz, a citizen of the United States and a resident of Lancaster, in the county of Lancaster, State of Pennsylvania, have invented a new, original, and ornamental Design for a Metal Cutting Machine or Similar Article, of which the following is a specification, reference being had to the accompanying drawing, forming part thereof.

Fig. 1 is a perspective view of a metal cutting machine or similar article showing my new design, and

Fig. 2 is a top plan view thereof.

I claim:

The ornamental design for a metal cutting machine or similar article, substantially as shown.

EWALD SCHUTZ.
